US00D736238S

(12) **United States Design Patent**
Kim

(10) **Patent No.:** **US D736,238 S**
(45) **Date of Patent:** **** Aug. 11, 2015**

(54) **DISPLAY SCREEN OR PORTION THEREOF
WITH GRAPHICAL USER INTERFACE**

(71) Applicant: **Samsung Electronics Co., Ltd.,**
Suwon-si, Gyeonggi-do (KR)

(72) Inventor: **Sun-Ho Kim**, Daegu (KR)

(73) Assignee: **Samsung Electronics Co., Ltd.,**
Suwon-si (KR)

(**) Term: **14 Years**

(21) Appl. No.: **29/456,248**

(22) Filed: **May 29, 2013**

(30) **Foreign Application Priority Data**

Feb. 23, 2013 (KR) 30-2013-0009507
